BLACKHEAD REMOVER TOOL

Gust A. Olson, 2030 Manning Ave., Los Angeles, Calif.
90025, and James S. Devine, 6029 Linda Way, Culver
City, Calif. 90230

Filed Jan. 24, 1966, Ser. No. 740

Term of patent 14 years

(Cl. D83—12)

FIGURE 1 is a side plan view of the blackhead remover tool showing our new design;

FIGURE 2 is an edge plan view taken from the right edge of FIGURE 1;

FIGURE 3 is a side plan view taken from the back side of FIGURE 1;

FIGURE 4 is an end plan view taken from the top of FIGURE 2;

FIGURE 5 is an end plan view taken from the bottom of FIGURE 3; and

FIGURE 6 is an enlarged plan view taken from the right side and lower end of FIGURE 2.

We claim:

The ornamental design for a blackhead remover tool, substantially as shown.
